UNITED STATES PATENT OFFICE.

THOMAS R. BARNES, OF MANSFIELD, OHIO.

FOLDABLE WALL-TABLE.

1,197,891.

Specification of Letters Patent. Patented Sept. 12, 1916.

Application filed July 14, 1913. Serial No. 779,050.

To all whom it may concern:

Be it known that I, THOMAS R. BARNES, a citizen of the United States, residing at Mansfield, in the county of Richland and 5 State of Ohio, have invented certain new and useful Improvements in Foldable Wall-Tables; and I do hereby declare the following to be a full, clear, and exact description of the invention, such as will enable others 10 skilled in the art to which it appertains to make and use the same.

This invention is a novel sanitary table particularly designed for use in pharmacies, hospitals, kitchens, and other places where 15 an easily cleansed, non-absorbent and hygienic table is desired; and its object is to provide a metallic table which can be attached to a wall and can be raised and held in usable position when desired; and when 20 it is not desired to use same it can be dropped down or folded against the wall so as to occupy less space, and be out of the way. I preferably make the table of cast, or pressed, iron or steel; or it may be made 25 partly of cast metal and partly of pressed metal; and the exposed portions of such table are enameled so that it presents an attractive appearance, and is germ and acid proof, and can be easily cleansed.

30 The accompanying drawings illustrate a practical table embodying the invention, and I will explain same fully with reference thereto; but the particular form or proportions of parts of the table shown in the 35 drawings are capable of variation while retaining the essential novel features and advantages of the invention.

In said drawings—Figure 1 is a perspective view of the complete table extended in 40 operative position; Fig. 2 is a rear view thereof with the table dropped or folded. Fig. 3 is a part side elevation and part sectional view of the table, folded.

The table as shown comprises, in brief, a 45 shelf bracket portion adapted to be attached to the wall; a top hinged to the bracket portion; a wall fixture on which the shelf bracket is supported; and swingable members attached to the wall whereby the top 50 portion is supported in horizontal position when in use, and can be folded against the wall under the shelf bracket and behind the top when the latter is dropped to folded position.

The wall fixture preferably consists of a 55 metal bar or casting having a main horizontal portion 1 provided in its upper rear side with pockets or notches 1^a, and having depending end portions 1^b which are provided at their lower ends with outwardly 60 extended projections 1^c.

The shelf bracket portion 2 is adapted to cover the wall fixture 1, and is provided with depending lugs 2^a at its upper rear edge which are adapted to engage in the 65 pockets 1^a in the wall fixture so as to sustain the shelf portion thereon. The shelf bracket also has depending end portions 2^b which extend below the ends 1^b of the wall fixture and give the shelf bracket a very 70 firm bearing against the wall and lessen the tilting strain on the shelf bracket when the shelf is loaded. These end portions 2^b of the shelf bracket are provided with inwardly projecting lugs 2^c that are adapted 75 to engage the projections 1^c of the wall fixture, see Fig. 2, and assist in holding the shelf bracket firmly in position upon the wall fixture and against the wall.

The shelf bracket has a forwardly projecting shelf portion 2^e; and to the outer edge of this shelf is hinged the inner edge of the table top 3, which as shown is provided on its rear edge with a longitudinal horizontal hinge portion 3^a transfixed by 80 a rod or bolt 2^f, that is secured to and between the upper ends of the portions 2^b adjacent the shelf portion, and adjacent the front edge of the shelf 2^e; so that when the table top is raised to horizontal position its 85 upper surface is substantially flush with the shelf 2^e and forms an extension of the top surface of the shelf.

The table top 3 may be conveniently supported in raised position by any suitable 90 means. I prefer to use two adjustable brackets 4 which are swingably supported below the shelf by means of pintles 4^a on their upper ends engaging eyes 1^m on the fixture 1 and by means of pintles 4^b on their 95 lower ends engaging eyes 6^b in small brackets or hinge members 6 fastened to the wall at suitable points. These brackets 4 can be swung inwardly beneath the shelf and against the wall and behind the dropped 100 table top, as indicated in Figs. 2 and 3, when it is desired to lower the table top; and the brackets 4 can be turned outward at right 105

angles to the wall to support the top 3 in raised position, as shown in Fig. 1; and as indicated in dotted lines, in Fig. 3.

These parts when properly assembled 5 form a compact, neat substantial sanitary wall table; the exterior surfaces of the shelf and table top are preferably finished in white enamel, imparting an attractive cleanly appearance to the table and enhancing its utility and serviceability. Small 10 articles can remain upon the shelf portion when the table top is lowered. When the top is lowered, as shown in Fig. 3, the table occupies very little room; and it is particularly desirable for use in small 15 rooms, or where it is preferred to have the table out of the way when not in use. As shown in Fig. 1 straps *r* may be hooked over the upper edge of the shelf portion; and an enameled iron rolling-pin *R* supported thereon; such a rolling-pin is usually 20 sold with the table, but forms no part of the present invention.

What I claim is:

25 1. A sanitary foldable wall table comprising a wall fixture having a main horizontal portion and depending end portions, a bracket having a main horizontal portion and depending end portions fitting over the 30 main and end portions of said fixture, and also having a shelf thereon, interengaging means on said fixture and bracket for detachably securing them together without other fastening means, a table top hinged 35 to said bracket so as to form an extension of the shelf thereon when in raised position, and means for supporting said top when raised; said means being adapted to swing back behind said top when the latter is 40 lowered.

2. In a table, the combination of a slotted wall fixture, an integral shelf bracket having a shelf portion and lugs at its upper edge adapted to engage the slots of the wall fixture and having integral end portions extending outwardly as far as the shelf portion and located below it; with a top hinged to the said end portions adjacent the outer edge of the shelf; and means for supporting 45

the top in raised position, said means being 50 foldable beneath the shelf and behind the top when the top is lowered.

3. In combination, a wall fixture, a bracket supported on said fixture and having a shelf and pendant end portions integral therewith 55 overlying and concealing said fixture, interlocking means on said fixture and bracket for detachably supporting the bracket on the fixture, a table top hinged to said bracket and adapted when raised to form an extension 60 of the shelf on said bracket and to swing downwardly substantially parallel with the wall on which it is supported; said fixture having recesses in the upper edge thereof and pendant end portions with lateral projections, and said bracket having pendant lugs adapted to engage said recesses and pendant end portions with inwardly extending lugs engaging said lateral projections; and means for supporting said 70 table top in a raised position; said means being adapted to swing back behind said top when the latter is lowered.

4. A foldable wall table comprising a wall fixture consisting of a metal bar having 75 a main horizontal portion provided with notches in its upper edge and with depending end portions having outwardly extended projections, a shelf bracket provided with depending end portions having inwardly 80 projecting lugs adapted to lie behind said outwardly extended projections and with depending lugs engaging said notches, whereby said shelf bracket is suspended from said fixture, a table top hinged to said 85 shelf bracket so as to form an extension of the shelf thereon when in raised position, and means for supporting the table top in its raised position; said means adapted to swing back behind the top and the latter 90 adapted to swing downwardly in front of said means.

In testimony whereof I affix my signature in the presence of two witnesses.

THOMAS R. BARNES.
